UNITED STATES PATENT OFFICE.

CHARLES W. VAN WYE, OF FREEPORT, KANSAS.

ADJUSTABLE SIEVE.

SPECIFICATION forming part of Letters Patent No. 761,561, dated May 31, 1904.

Application filed January 12, 1903. Serial No. 138,734. (No model.)

To all whom it may concern:

Be it known that I, CHARLES W. VAN WYE, a citizen of the United States, residing at Freeport, in the county of Harper, State of Kansas, have invented certain new and useful Improvements in Adjustable Sieves; and I do hereby declare the following to be a full, clear, and exact description of the invention, such as will enable others skilled in the art to which it appertains to make and use the same.

This invention relates to sieves for grain-separators; and it has for its object to provide a sieve including sections each having a depending deflector-plate so arranged that the air-blast will pass vertically through the sieve or at right angles to the upper faces of the sections of the sieve instead of transversely thereof, so that the chaff and other light matter will be first raised bodily from the sieve before it is carried laterally therefrom. This action serves to better separate the light particles from the grain, which by its weight remains upon the sieve, and the usual large quantity of grain is not blown into the return elevator.

A further object of the invention is to provide a construction including a simple and efficient arrangement wherein the sections of the sieve may be readily shifted with respect to each other to discharge the contents of the sieve.

In the drawings forming a portion of this specification, and in which like numerals of reference indicate similar parts in the several views—

Figure 1 is a bottom perspective view showing a sieve embodying the present invention. Fig. 2 is a longitudinal section of the sieve. Fig. 3 is a top plan view.

Referring now to the drawings, the sieve comprises a frame, including end portions 5 and 6 and the side portions 7 and 8, which latter project above the end portions. Within the frame are disposed transversely sections of sieves each of which is in the form of a plate 9, having at its end trunnions 10, which are journaled in the sides of the frame, and one edge of each of the plates is bent

downwardly at right angles to form a deflector 11, the body portion of the plate having perforations 12 therethrough. The arrangement of the deflecting-flanges of the several plates is such that the air-blast passing longitudinally beneath the screen will be caught by the flanges and deflected upwardly through the perforations, it being noted that the deflecting-flanges lie at acute angles to the plate, so that the blast may be made to traverse each plate before it strikes the flange of that plate, and in consequence passes directly upwardly through the perforations and through whatever openings there may be between two plates, so that in order to blow the grain from the screen the blast must lift it bodily and then carry it laterally, and the grain being heavy this does not occur. If the air-blast struck the opposite sides of the flanges and they depended at obtuse angles to their respective plates, then should two plates be not in close contact the air would pass between the plates and would tend to pass laterally over the tops of the plates, and thus blow the grain from the plates with the chaff. To shift the plates and separate them to precipitate the grain therefrom after it is cleaned, a rock-shaft 13 is provided and is mounted in suitable bearings upon the end of the screen-frame, said rock-shaft having crank-arms 14, as illustrated.

Depending from the plates of the screen adjacent to the ends thereof are arms 15 and 16, to which are pivotally connected the shift-rods 17, which are connected in turn to said crank-arms, so that when the rock-shaft is operated the plates of the screen will be oscillated to lie with their body portions in a common horizontal plane or to lie in separate parallel planes at angles to a horizontal plane.

Extending longitudinally of the upper side of the frame and connected to the ends thereof are brace-rods 18, which give rigidity to the structure.

It will be understood that the rock-shaft may be operated by means of a handle or in any suitable manner, that modifications of the specific construction shown may be made,

and that any suitable materials and proportions may be used for the various parts without departing from the spirit of the invention.

What is claimed is—

- 5 A screen for threshing-machines comprising a frame having brace-rods connecting its ends, a plurality of perforated plates rockingly mounted for movement to lie in a common plane or at angles to said plane, each of
- 10 said plates having a flange at one edge parallel with the axis of movement of the plate and

depending at an angle thereto to arrest a blast after its passage across the plate and deflect it through the perforations, and means for rocking the plates.

15

In testimony whereof I affix my signature in presence of two witnesses.

CHARLES W. VAN WYE.
